UNITED STATES PATENT OFFICE.

GEORGE M. URIE, OF KANSAS CITY, MISSOURI.

DESIGN FOR A SAD-IRON.

SPECIFICATION forming part of Design No. 30,336, dated March 14, 1899.

Application filed January 17, 1899. Serial No. 702,491. Term of patent 7 years.

To all whom it may concern:

Be it known that I, GEORGE M. URIE, a citizen of the United States, residing at Kansas City, in the county of Jackson and State of Missouri, have invented and produced a new and original Design for Sad-Irons, of which the following is a specification, reference being had to the accompanying drawings, forming part thereof.

10 Figure 1 is a side elevation of a sad-iron, showing my new design. Fig. 2 is a plan view of the bottom, and Fig. 3 is a sectional view taken transversely of Fig. 1 on the line 3 3.

The body of the iron A is elliptical in plan view and its sides are somewhat slanted or flared from the top down. The handle B is shaped approximately on the arc of a circle and is attached to projections on the iron-top.

15 The body of the iron is provided with a series of holes or openings *a* near the base and is cut away at the top to form a slot C in conjunction with the top of the iron. The con-

tour of this slot or cut-away portion C is rectilinear in form and has at each end an angular continuation extending upward a short 25 distance. This form of slot is secured by having the two side flanges *c c'* of the top C' smaller in dimensions than the embrasures *a' a''* in the sides of the iron into which they depend. These embrasures extend only a 30 portion of the length of the sad-iron, and the latter is hollow, as shown.

Having described my invention, what I claim as new, and desire to secure by Letters Patent of the United States, is—

35 The design for a sad-iron, as herein shown and described.

In testimony whereof I affix my signature in the presence of two witnesses.

GEORGE M. URIE.
